UNITED STATES PATENT OFFICE.

CHARLES E. PAGE, OF DENVER, COLORADO, ASSIGNOR TO THE PAGE SADDLE COMPANY, OF SAME PLACE.

DESIGN FOR A BICYCLE-SEAT PAD.

SPECIFICATION forming part of Design No. 26,978, dated April 27, 1897.

Application filed January 11, 1897. Serial No. 618,887. Term of patent 7 years.

To all whom it may concern:

Be it known that I, CHARLES E. PAGE, a citizen of the United States of America, residing at Denver, in the county of Arapahoe and State of Colorado, have invented and produced a new and original Design for Pads and Cushions for Bicycle-Seats; and I do declare the following to be a full, clear, and exact description of the invention, such as will enable others skilled in the art to which it appertains to make and use the same, reference being had to the accompanying drawings, which form a part of this specification.

Figure 1 is a top plan view of my new design for a rubber bicycle-seat pad. Fig. 2 is a bottom plan view of the same. Fig. 3 is an edge view of the same.

The leading feature of my design consists of a substantially semicircular-shaped bicy-

cle-seat pad or cushion in plan and of wedge-shape form in thickness, having a series of cells extending into it between narrow ribs or partitions to within a thin shell of the material which forms the surface of the opposite side.

The thick end and center of the pad are designed to rest on the center and cantle of the saddle while the tapering end rests close to the side front edge of the saddle.

What I claim is—
The design for a bicycle-seat pad, substantially as shown and described.

In testimony whereof I affix my signature in presence of two witnesses.

CHARLES E. PAGE.
